CLAIM

The ornamental design for a salon neck rest, as shown and described.

DESCRIPTION

FIG. 1 is a front elevational view of a salon neck rest showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a top, front and right side perspective view thereof on a reduced scale.

The broken line showing of a shampoo basin in FIG. 7 is for illustrative purposes only, and forms no part of the claimed design.
